Primary Examiner — Derrick E Holland*Assistant Examiner* — Jennifer O King(74) *Attorney, Agent, or Firm* — Keusey & Associates, P.C.(57) **CLAIM**

The ornamental design for a mating section of electrical connector with locking tabs, as shown and described.

DESCRIPTION

FIG. 1 is a top, front, left side perspective view of my new design of a mating section of electrical connector with locking tabs.

FIG. 2 is a front side elevational view thereof.

FIG. 3 is a right side elevational view thereof.

FIG. 4 is a left side elevational view thereof.

FIG. 5 is a top plan view thereof.

FIG. 6 is a bottom plan view thereof; and,

FIG. 7 is a rear side elevational view thereof.

The broken lines shown in FIGS. 1, 2, and 7 represent portions of the mating section of electrical connector with locking tabs that form no part of the claimed design.
